UNITED STATES PATENT OFFICE.

PETER F. VANDENBOSSCHE, OF HARRISON TOWNSHIP, MACOMB COUNTY, MICHIGAN.

SHOTGUN-BARREL.

1,013,974.

Specification of Letters Patent.

Patented Jan. 9, 1912.

Application filed February 2, 1911. Serial No. 606,258.

To all whom it may concern:

Be it known that I, PETER F. VANDENBOSSCHE, a citizen of the United States, residing in the township of Harrison, county of Macomb, State of Michigan, have invented a certain new and useful Improvement in Shotgun-Barrels, and declare the following to be a full, clear, and exact description of the same, such as will enable others skilled in the art to which it pertains to make and use the same, reference being had to the accompanying drawings, which form a part of this specification.

This invention relates to shot gun barrels and its object is a gun barrel to which may be attached other comparatively short lengths of barrel of the same or differing choke. A shot gun provided with a barrel having a cylinder bore will scatter a charge of shot issuing therefrom while a barrel having a choke bore will throw a charge of shot in a more compact formation and to a greater distance than will a cylinder bore with the same powder charge. Consequently a single barreled gun of any particular choke is primarily adapted for a certain class of service and is comparatively unadapted for other classes of service. The utility of the invention herein disclosed is in adapting a gun for use in various classes of service. A sportsman in a day's travel through the country usually encounters conditions where a gun of a certain choke would do the most effective work. If the gun carried is not of that choke the results desired are not attainable. With the arrangement of the barrel herein shown, other short lengths of barrel of the desired choke may be attached thereto and the gun thereby adapted for service under any of varying conditions that may be encountered. By carrying a number of these short lengths of barrel, each of a different degree of choke, the range of service for which the gun is adapted is greatly increased. These and other objects and novelties of the invention are hereinafter more fully described and claimed. A means by which these objects may be accomplished is shown in the drawings in which—

Figure 1 is a perspective view of a part of a gun barrel in which my invention is embodied. Fig. 2 is a longitudinal section thereof. Fig. 3 is a bottom view of the barrel showing the clamp by means of which the short length of barrel is secured thereto.

Similar characters refer to similar parts throughout the drawings and specification.

The main barrel 1 has an enlarged end 2 which is counterbored and threaded for the reception of the short length of barrel 3. The end 4 of the barrel 3 is of the exact bore of the barrel 1 and the end 5 may be of the same or smaller bore. If the end 5 is less in diameter than the end 4, with the bore gradually decreasing from one end to the other, it is what is termed choke bored and if the barrel is of the same diameter throughout its length, it is cylinder bored. The enlarged end 2 of the barrel 1 is not threaded the entire length of the counterbore and the part not threaded is slotted on the under side at 6. At or near the end of the part 2 and at each side of the slot are lugs 7 and 8. The lug 7 is threaded and the lug 8 is bored for the reception of the screw 9 by means of which the auxiliary barrel 3 is securely held in place. The screw 9 has a head 10 which is provided with a lever 11 reciprocatable in an aperture in the head and by means of which the screw may be turned and the barrel 3 clamped in place. Otherwise the barrel 3 might become loosened in use. The counterbore of the part 2 is of the proper size to allow the auxiliary barrel to be easily inserted therein and the clamp holds the two barrels in alignment.

I have found experimentally that auxiliary barrels of less than a foot in length are sufficient for the purpose herein outlined and that slight differences in the degree of choke in barrels of such short lengths will produce a decided difference in the formation of a shot charge issuing therefrom. It is to be understood, however, that auxiliary barrels of greater length than that specified may be used if desired.

Having thus briefly described my invention and its operation, what I claim is—

1. A shot gun barrel comprising a main barrel and an auxiliary barrel, the main barrel having an enlarged and contractible end integrally formed therewith adapted to receive an end of the auxiliary barrel, and means for contracting said enlarged end to maintain the barrels in fixed relation.

2. A shot gun barrel comprising a main barrel and an auxiliary barrel, the main barrel having an enlarged end integrally formed therewith, said enlarged end being threaded for a portion of its length to receive the threaded end of the auxiliary bar-

rel, the unthreaded portion of said enlarged end being slotted on one side and having an ear or lug on each side of the slot, and a screw carried by the lugs adapted to contract the slotted portion of the enlarged end.

3. A shot gun barrel comprising a main barrel and an auxiliary barrel, the main barrel having an enlarged end counterbored and threaded for the reception of the auxiliary barrel, the auxiliary barrel being of a different choke than the main barrel and

having a threaded end whereby it may be screwed into the enlarged end of the main barrel, and a clamp connected with said enlarged end whereby the barrels may be 15 maintained in axial alinement.

In testimony whereof, I sign this specification in the presence of two witnesses.

PETER F. VANDENBOSSCHE.
